ROTARY VARNISHING PRESS

Frank T. Sheedy, Burlingame, and Louis Traung, San Francisco, Calif., assignors to The Traung Company, San Francisco, Calif., a copartnership composed of Charles F. Traung, Louis Traung, L. H. Jackson, H. W. Johnson, H. T. Gardner, and Frank T. Sheedy

Application April 5, 1935, Serial No. 14,798

13 Claims. (Cl. 91—13)

This invention relates to the art of printing in general, and in particular to apparatus or presses for applying a layer of varnish over printed sheets so that they will have a high gloss when dry and will also be waterproof. The principal object of the present invention is to provide in one rotary style press machine, means for effectively dusting off the surface of the printed matter and immediately thereafter as a continuous 5 operation giving the dusted surface of each sheet one or more coats of varnish, and then passing out the heavily varnished sheet to a suitable drying conveyor. Other objects and advantages of the invention will appear in the following 10 description and accompanying drawing.

In the drawing Fig. 1 is an elevation showing the relation of cylinders and rolls, grippers, wipers, etc., arranged in accordance with our invention, and Fig. 2 is a detail view of the varnishing 15 roller.

Briefly described, the invention comprises a rotary press-like machine 1 in which the dry printed sheets are fed to a transfer cylinder 2 and transferred to another or dusting cylinder 3 where several revolving dusting rolls 4 clean off 20 all the dust, particularly any loose bronze powders which would injure the appearance of the varnished sheet. A vacuum connection 5 draws out all of the loosened dust, a final holding roll 6 prevents the sheet from being pulled from the grippers of the dusting cylinder, and the sheet is taken over by another transfer cylinder 7 to a larger drum or varnishing cylinder 8 which is 25 twice the diameter of the preceding cylinders and receives two of the dusted sheets in tandem and whereon the one or two coats of varnish are applied by varnish rolls 9, 10 which are spaced about a quarter around the circumference of the drum so as to give a short interval of time for 30 the varnish from the first roll to sink into the paper before the second coat is applied. From the drum the varnished sheets are delivered to grippers on endless chains 11 to be carried on tapes 12 and delivered to a second conveyor or 35 tapes 13 which may carry them through any type of drying box or oven desired.

As the invention resides in the general combination and not in the details of actuation, adjustment, gripper operation, drive, etc., and as 40 all such minor details are well known in the printing press art, they are not described here nor shown in the drawing as it would serve no purpose but to confuse the issue. Suffice it to say, however, that the cylinders are all slightly 45 adjustable and set to clear one another by about 50 55

a sixteenth of an inch and all are geared together to travel at a uniform surface speed as by gears 14, 15, 16 and 17, and others, not shown, to revolve in the directions indicated; also the cleaning or dusting rolls 4 are suitably driven in 5 counter surface direction to cylinder 3 and at a relatively high speed (about 800 R. P. M. as against about 40 R. P. M. for cylinder 3), while holding roll 6 is driven in the same surface direction as cylinder 3 and at the same surface speed. 10

In further detail, the printed paper sheets are fed one by one by hand or by any suitable automatic feeder at the point 18 face down to the upper side of cylinder 2 to be gripped by its grippers 19 and delivered to the grippers 20 of 15 cylinder 3 so that the sheet travels downwardly and face outward past the several cleaning rollers 4 and then past the holding roll 6.

Dusting rolls 4 may be covered with soft cloth, or of soft cloth disks, or brushes, and are each 20 adjustable toward and from cylinder 3 by any suitable means or the eccentrics indicated at 21, and each is provided with a scraper of any desired form, but here shown as a square bar 22 with one of its corners set to impinge the revolving dusting roll. These bars may be 25 revolved to bring any of their corners into action, and are also adjustable toward and from the dusting rolls as by their mounting brackets 23.

Holding roll 6 is similarly mounted to rolls 4 30 and is preferably made up of a series of spaced rubber-covered disks rolling against the paper at same surface speed as cylinder 3. The vacuum or suction connection 5 includes a sheet metal or other housing 24 substantially enclosing the dusting rolls as indicated and slanted to an exhaust pipe 5 in turn leading to any suitable type of 35 exhaust fan.

From the dusting cylinder, the grippers 25 of transfer cylinder 7 carry the cleaned sheets to 40 the varnishing drum or large cylinder 8 which, as stated, is twice the diameter of the other cylinders, and has two gaps at opposite points in its diameter fitted with grippers 26, 27 each timed to pick a sheet from grippers 25 of cylinder 7 as 45 the latter release it. This large cylinder preferably carries a rubber blanket 38 over each impression space tensioned over a bar 39 at each end, as well as felt or other packing beneath the blankets, and operating against the under side 50 of the large cylinder are the two varnishing rolls 9 and 10, preferably of some rubber composition, and which rolls each bear against a larger steel roll 29 revolving in a varnish fountain or trough 55, while an adjustably mounted squeegee roller 55

31 regulates the amount of varnish transferred to roller 9 or 10. Circle 32 designates the pitch circle of a drive gear driving one end of roll 29 from gear of cylinder 6 or its equivalent in surface speed.

In case a sheet is missed by the feeder, or torn before it arrives at the varnishing cylinder, the varnish rolls may be manually or automatically tripped or thrown off so as not to smear up the 10 blankets. The means for accomplishing this is of many forms, all well known in the art and not a specific part of the present invention, hence here generally numbered 33 controlled by bell crank rods 34, 35, 36, which may be hooked up 15 to the feeder apparatus in any of the known ways. The setting of the varnish roll trip mechanism should be so adjusted that in case a sheet is missed at cylinder 2, by the time that sheet should have been to cylinder 8 the trip will 20 throw off the first varnish roll 9, then throw off the second varnish roll 10 but not before it has finished the preceding sheet.

The composition varnish rolls 9 or 10 may of course be grooved as indicated at 37 in Fig. 2 25 to provide bare margins, as on labels, etc.; also, as it seems almost superfluous to state, the padding under the blankets of the impression drum may be cut away so that the varnish layer will terminate just at the end of the printed sheet.

30 From the varnishing cylinder the sheets are taken by gripper bars 40 on the chains 11 and carried along the moving tapes 12 which pass the sheets to tapes 13 which latter travel a trifle faster. Tapes 41 above the sheets travel at the same speed as tapes 13 and are arranged over 35 the uncoated margins as may be left by grooves 31 of the varnish rolls.

Chains 11 are conveniently driven by a gear 42 in mesh with the large cylinder gear, as also are 40 tapes 12 through an intermediate gear 43.

The various sets of grippers are of course released from the sheets just before the next set 45 grips the sheet in the manner well known in the art and therefore not detailed herein.

45 In operation the large or varnishing cylinder is driven by any suitable means at about 20 R. P. M. and the dusting rolls 4 either geared up from any suitable revolving element, or all driven by a separate motor, not shown, to ten or twenty times 50 as fast as cylinder 3 as described.

While we prefer to have the varnishing cylinder twice the size of the others, so that two sets of varnish-applying rolls may be spaced apart and give a moment for the first coat to sink in 55 before the outer, and perhaps heavier coat is applied, it is evident that the same result may be had by having the cylinders all small or for one sheet only and feeding every other revolution and retaining the sheet two revolutions on the varnishing cylinder so as to get two coats of varnish from one fountain only. Also, it is evident that instead of feeding the sheets over the top of a transfer cylinder 2, this could be dispensed with and the sheets fed down to cylinder 3, but we 65 prefer the first arrangement, as shown in the drawing, as it gives more room under cylinder 3 for the dusting rollers.

The press may, of course, be made in any size to handle sheets of any dimensions desired.

70 Our machine as above described overcomes the use of separate dusting and varnishing machines and gives much better work as it insures each sheet being perfectly cleaned of loose particles and at once passed over the varnishing cylinder 75 before it has had time to pick up any dust or

any further bronze powder could be released from its surface, while at the same time it speeds up the work in reducing operations.

Having thus described our improved rotary varnishing press, what we claim is:

We claim:

1. A rotary varnishing press comprising a frame, a series of rotatably mounted cylinders on said frame geared together, means for transferring a sheet of paper from one cylinder to the other throughout the series during their rotation, a soft cleaning roll arranged to revolve against the face of the sheet while on one of the cylinders, means for applying a layer of varnish on said face of the sheet while on a later cylinder 15 of the series, and means for conveying the varnished sheet from the latter cylinder.

2. A rotary varnishing press comprising a frame, a series of rotatably mounted cylinders on said frame geared together, means for transferring a sheet of paper from one cylinder to the other throughout the series during their rotation, a soft cleaning roll arranged to revolve against the face of the sheet while on one of the cylinders, means for applying successive layers of 25 varnish on said face of the sheet while on a later cylinder of the series, and means for conveying the varnished sheet from the latter cylinder.

3. A rotary varnishing press comprising a frame, a series of rotatably mounted cylinders on 30 said frame geared together, means for transferring a sheet of paper from one cylinder to the other throughout the series during their rotation, a plurality of soft cleaning rolls arranged to revolve against the face of the sheet while on one 35 of the cylinders, scrapers arranged to bear against the cleaner rolls for removing loose particles therefrom, means for applying a layer of varnish on said face of the sheet while on a later cylinder of the series, and means for conveying the varnished sheet from the latter cylinder.

4. A rotary varnishing press comprising a frame, a series of rotatably mounted cylinders on said frame geared together, means for transferring a sheet of paper from one cylinder to the other throughout the series during their rotation, a plurality of soft cleaning rolls arranged to revolve against the face of the sheet while on one of the cylinders, scrapers arranged to bear against the cleaner rolls for removing loose 45 particles therefrom, suction means arranged for exhausting the removed dust, means for applying a layer of varnish on said face of the sheet while on a later cylinder of the series, and means for conveying the varnished sheet from the latter 50 cylinder.

5. In a construction as specified in claim 1, means for tripping the varnish-applying means out of action in emergencies.

6. A rotary varnishing press for printed sheets 60 which comprises a plurality of rotatably mounted cylinders geared together in a series for uniform surface speeds, means gripping successive sheets of paper by the first cylinder of the series and passing the sheets successively to the succeeding cylinders, rotary cleaning rolls arranged to bear against the sheets for cleaning the same of dust and loose material while on one of the cylinders, and a pair of spaced varnish-applying fountains positioned to operate against the sheets 65 while on the last cylinder of the series.

7. A rotary varnishing press for printed sheets which comprises a plurality of rotatably mounted cylinders geared together in a series for uniform surface speeds, means gripping successive sheets 70

of paper by the first cylinder of the series and passing the sheets successively to the succeeding cylinders, rotary cleaning rolls arranged to bear against the sheets for cleaning the same of dust and loose material while on one of the cylinders, and a pair of spaced varnish-applying fountains positioned to operate against the sheets while on the last cylinder of the series, said last cylinder being twice the diameter of the preceding cylinders of the series and provided with gripping means arranged to take two sheets in succession therefrom in tandem relation in each revolution.

8. A rotary varnishing press for printed sheets which comprises a plurality of rotatably mounted cylinders geared together in a series for uniform surface speeds, means gripping successive sheets of paper by the first cylinder of the series and passing the sheets successively to the succeeding cylinders, rotary cleaning rolls arranged to bear against the sheets for cleaning the same of dust and loose material while on one of the cylinders, and a pair of spaced varnish-applying fountains positioned to operate against the sheets while on the last cylinder of the series, said last cylinder being twice the diameter of the preceding cylinders of the series and provided with two blankets with tensioning means and two sets of gripping means arranged to take two sheets in succession therefrom in tandem relation in each revolution.

9. A rotary varnishing press for printed sheets comprising a sheet-receiving cylinder provided with grippers and arranged to grip the sheets face in, a second cylinder in direct gear with the first and provided with grippers arranged to take the sheet from the first cylinder and carry it face out, a plurality of dusting rolls arranged to revolve at relatively high speed against the face of the sheet while on said second cylinder, a third cylinder geared directly to the second cylinder and provided with grippers arranged to take the sheet from the second cylinder face in, a fourth cylinder in direct gear with the third cylinder provided with grippers arranged to take the sheet from the third cylinder and carry it face out, and a varnish fountain provided with

a varnish roll arranged to bear against the face of the sheet while on said fourth cylinder.

10. A rotary varnishing press for printed sheets comprising a sheet-receiving cylinder provided with grippers and arranged to grip the sheets face in, a second cylinder in direct gear with the first and provided with grippers arranged to take the sheet from the first cylinder and carry it face out, a plurality of dusting rolls arranged to revolve at relatively high speed against the face of the sheet while on said second cylinder, a third cylinder geared directly to the second cylinder and provided with grippers arranged to take the sheet from the second cylinder face in, a fourth cylinder in direct gear with the third cylinder provided with grippers arranged to take the sheet from the third cylinder and carry it face out, and a pair of spaced varnish fountains provided with varnish rolls arranged to bear against the face of the sheet while on said fourth cylinder.

11. In a construction as specified in claim 9, said fourth cylinder being twice the diameter of the third cylinder and provided with two sets of grippers at opposite points in its diameter arranged to take two sheets in succession at each revolution from the third cylinder in tandem arrangement.

12. In a construction as specified in claim 9, said fourth cylinder being twice the diameter of the third cylinder and provided with two sets of grippers at opposite points in its diameter arranged to take two sheets in succession at each revolution from the third cylinder in tandem arrangement, and conveyor means geared to the press arranged to positively grip and take the varnished sheets from the fourth cylinder.

13. In a rotary varnishing press as specified in claim 6, a traveling conveyor arranged above the series of cylinders and provided with means to positively grip and take the varnished sheets in succession from the last cylinder of said series and convey them from the press.
